TASSO D. METROPOLE AND TASSOS M. COTTAKIS, OF NEW YORK, N. Y.

TYPEWRITING MACHINE.

Application filed May 25, 1923. Serial No. 641,329.

The invention relates to a novel automatic typewriter mechanism, and more particularly to such a mechanism for automatically producing a controller sheet, and for producing complete and successively individually addressed letters or other matters from such a controller sheet.

Objects and advantages of the invention will be set forth in part hereinafter and in part will be obvious herefrom, or may be learned by practice with the invention, the same being realized and attained by means of the instrumentalities and combinations pointed out in the appended claims.

The invention consists in the novel parts, constructions, arrangements, combinations and improvements herein shown and described.

The accompanying drawings, referred to herein and constituting a part hereof, illustrate one embodiment of the invention, and together with the description, serve to explain the principles of the invention.

Of the drawings:—

Fig. 1 is a side elevation of a mechanism constructed in accordance with the principles of the invention for making the perforated controller sheet and for operating a machine by the perforated controller sheet;

Fig. 2 is a side elevation looking at Fig. 1 from the left;

Fig. 3 is a fragmentary detail of the cylinder which cooperates with the character selecting fingers in operating the typewriter from the controller sheet;

Fig. 4 is an elevation of the cylinder of Fig. 2, looking therat from the left, and showing also the feed mechanism therefor, which is likewise shown at the left central part of Fig. 1;

Fig. 5 is an elevation, looking at Fig. 3 from the right, and showing also the detent mechanism for holding the cylinder in position;

Fig. 6 is a side elevation of the feed cylinder for the controller strip while it is being perforated;

Fig. 7 is an end elevation, looking at Fig. 6 from the left, and showing the feeding or actuating means for the cylinder, which is likewise shown at the right lower middle part of Fig. 1;

Fig. 8 is an elevation, corresponding to Fig. 6, looking therat from the right, and showing the detent or positioning mechanism for the cylinder;

Fig. 9 shows the cylinder for feeding the controller strip for the repeated letter body and a series of successively used controller strips for addresses for recurrently printing the same letter with successive different names and addresses;

Fig. 10 is a fragmentary showing of the address strip; and

Fig. 11 is a view looking at Fig. 9 from the left.

Referring now by way of example to the embodiment of the invention, exemplarily illustrated in the accompanying drawings, the frame of a typewriter machine is shown at 1 and the key lever mechanism is shown fragmentarily and somewhat diagrammatically at 2, but it will be understood that these mechanisms may be of any usual or suitable form. The automatic controlling mechanism is contained in a casing 3, the feet 4 of the typewriter resting in supports or receptacles 5 on the top of the casing for the automatic controlling mechanism.

In accordance with certain features of the invention, a single connection from the typewriter key levers is provided for both making the controller strip and for thereafter operating the typewriting machine therefrom. In Fig. 1, the casing is indicated more or less diagrammatically, and the front plate or side, which provides bearings for the various shafts is removed therefrom to more clearly show the inclosed mechanism. As so embodied, a series of rods 10 correspond to, and are in operative relation at their top ends with, the various key levers 2 of the typewriter, there being a rod or bar 10 for each key lever.

The embodied form of connection therebetween comprises a slot 11, formed in the upper part of the bar 10 beneath the key lever 2, and an adjustable stop-screw 12, mounted in the bar 10 and engaging with the key lever on the top thereof. Thus when the key lever 2 is depressed, the pin 11 will depress the bar 10 therewith. Also, when the bar 10 is drawn downwardly, the screw 12 will draw the key lever 2 downwardly therewith, to cause the typewriter to print the selected letter.

Referring first to the mechanism for making the controller strip, the series of bars 10 have their lower ends longitudinally reciprocal in apertures in a guide plate 16, which plate extends across between, and is fixed to, the side walls of the casing. The controller

strip α to be perforated, comes into the machine over a supporting plate 17, and a hand-operated feed roller 18 serves to thread it through the machine over the plate 17. 5 The shaft 19 of the hand roller is journaled in the side plates of the machine.

A series of spring-operated, longitudinally-reciprocable punches are provided, equal in number to the typewriter key levers 10 2, these punches perforating the controller sheet α in conformity to the actuation of the key levers. As embodied, the perforating punches 20 are reciprocably carried in apertures in a supporting and guiding plate 21, 15 extending horizontally across the machine and they are also similarly carried in apertures in a bottom guide plate 22, spaced from and extending across beneath the guide plate 21. The perforating punches 20 are 20 held resiliently in non-operating position by suitable means, such as coiled, helical springs 23, the lower ends of which bear against plate 22 and the upper ends against stop pins 24, which pins also limit the upward 25 movement of pins 20. Beneath the punches 20 is a horizontally and transversely-disposed die block 26, having apertures 27 corresponding to the pins 20.

The embodied form of means for selectively perforating the controller sheet α in accordance with the actuation of the key levers 2, and for feeding the controller sheet forward, comprises a bearing rod 36 which extends across the casing and is supported 30 in elongated slots 37 in the side walls thereof, so as to be horizontally slidable to and fro. Pivoted on rod 36 are a series of levers 38 corresponding to, and in operative relation with, the respective rods 10, the forward end of these levers projecting into longitudinally disposed slots or openings 39 in the rods or bars 10.

Fixed in each of the slots 39 and extending thereacross is a pin 40, which actuates 45 the corresponding lever 38 when the corresponding bar 10 is depressed by its key lever 2, and which is also used to operate the key lever as later described. Each of the levers 38 has a downwardly extending projection 41 adapted to cooperate with the corresponding punch 20. Thus when a key lever 2 is depressed, the corresponding bar 10 is depressed therewith, and its pin 40 strikes the corresponding lever 38, and the 50 corresponding punch 20 is driven through the sheet α to perforate it for the selected character or function of the typewriting machine.

Referring now to the mechanism for intermittently feeding the controller strip forward between successive perforations, a pair of levers 48 have mounted on the ends thereof a universal bar 47, which is located just beneath the various bars 10. The levers 48 65 are pivoted on a rod 49, which is eccentric-

ally mounted in a pair of discs 50 at either side of the mechanism, to be transversely moved thereby, the discs 50 being concentrically journaled at 51 in the side walls of the casing. The universal bar 47 is resiliently held against the underside of the plate 16 by suitable means, such as springs 52 acting on levers 48. At the other ends thereof, one of the levers 48 is in operative relation with a longitudinally disposed cam plate 53. 70 This cam plate cooperates with a cam roller 54, which is mounted at one end of a lever 55, pivotally supported at 56 on the machine frame.

A feed pawl 57 is pivotally connected at 80 58 to the lever 55. The tooth 60 of the pawl engages with ratchet teeth 61 formed on the feed roller 62 for the controller strip. A resilient feed roller 63 cooperates with the roller 62 to press the controller strip thereagainst and to cause it to feed accurately with the roller 62. Thus whenever a bar 10 is depressed in perforating the controller sheet, levers 48 are rocked by means of the universal bar, and cam 53 actuates lever 55 90 to operate roller 62 to feed the controller strip α one space.

Referring now to the embodied form of means for throwing the controller strip perforating mechanism out of operation, as is done when the controller strip operates the machine. A pair of arms 64 are pivotally connected to the transversely slidable rod 36. At their opposite ends 65, arms 64 are pivotally connected to a pair of levers 66, which levers are pivotally mounted at 67, and the lower ends of the levers are bifurcated as shown at 68 to straddle the rod 49. A tension spring 69 impels the feeding pawl 57 to its initial or feed-beginning position. 100 By rotating the disc 50 by a suitable hand wheel, for a semi-circumference, rod 49 is thereby moved through a semi-circumference, and levers 66 are rocked to slide the rod 36 to the right in Fig. 1. Bars 38 are 110 thereby moved to the right from beneath the actuating pins 40 in the respective rods 10, and are thus brought to inoperative position, so that the machine may be used for writing, as later described. The controller sheet perforating mechanism is then in the inoperative position.

A suitable detent and positioning mechanism for cylinder 62 during the perforating of the sheet α is provided, (Fig. 8). A detent lever 70 passes into and out of engagement with teeth 71 on cylinder 62, the lever being pivoted at 72. A link 73 which is pivoted at 75 to one of the lever arms 48, already described, has a forked end that straddles a pin 74 fixed in lever 70, and normally holds it out of engagement with teeth 71. A spring 77 between the levers resiliently impels detent lever 70 into engagement with teeth 71 when lever 48 is rocked in 130

counter-clockwise direction. By the foregoing mechanism, lever 70 will hold cylinder 62 stationary during the perforation of sheet α , and immediately thereafter link 73 will move detent lever 70 out of engagement with the teeth 71 on cylinder 62.

Referring now to the embodied form of mechanism for operating the typewriter from the prepared controller strip α , a series of plungers or detector pins or fingers 80 are longitudinally reciprocably mounted in a supporting and guiding block 81, which extends across the machine, the detector pins or fingers corresponding in number to the key levers 2. Cooperating with the fingers 80 is a roller 82, which supports and feeds the perforated controller strip α to present it to the pins 80, and having its surface formed to permit any pin 80 which finds its perforation in the controller strip to drop and thereby actuate the typewriter mechanism as hereinafter described. The feed roller 63 and a feed roller 84 preferably operate with the roller or cylinder 82 in feeding the strip α . The roller 82 is provided, accordingly, with annular circumferential recesses 86, just beneath each of the fingers or pins 80, so that any pin 80 may move downwardly whenever it finds a perforation y in the controller strip α .

Each of the pins 80 is provided with a head 87, and a compression spring 88 is seated on a pin 89 projecting from the top of the head 87 and is also seated in a recess 35 in a bar 90, and thereby resiliently presses the pin 80 downwardly. Mounted for longitudinal reciprocation in a horizontally disposed aperture in each of the heads 87 is an actuating pin, or interponent 94. The pins 40 94 have each a yoked head 95, which head straddles the tail 96 of a bell crank lever, which lever is pivoted on a rod 97, extending across the machine. The other end 98 of the bell crank lever extends through the corresponding slot 39 of the corresponding bar 45 10, and is adjacent to or rests upon the top side of its pin 40. A spring 99 resiliently supports and restores the various levers 98.

A reciprocating universal actuating bar or bail 108 extends across the machine, and when any of the fingers 80 is in the downward position through finding its perforation y in the controller strip α , its interponent 94 is brought into horizontal alinement with 55 and is actuated by the universal bar. When there is no perforation in the controller strip α corresponding to any finger or pin 80, the finger is supported in its up position by the controller strip, and its interponent 94 is above and clear of the actuating bail 108. The bail 108 is carried upon a pair of arms 109 of a pair of bell crank levers, which are pivoted at either side of the machine upon a rod 110. Fixed to one of said 60 levers is an arm 111, provided with a cam

70 roller 112, which rides on a cam 113, and is resiliently held thereto by a spring 114. Cam 113 is fixed on a shaft 116, which extends across and is journaled in the side walls of the machine casing.

Restoring means for bringing a pin 80 out of its perforation y and lifting or returning it to inoperative position preparatory to the forward feed of the controller strip, and finding another perforation y in the controller strip, are provided. As embodied, a universal bar 120 extends across the machine beneath the interponents 94. The bar 120 is supported at either end thereof in arms 121, fixed to a rod 122, which rod 80 extends across and is journaled in the side walls of the casing. Fixed to the rod 122 is an actuating arm 123, which arm is provided with a cam roller 124, running on a cam 125, the cam being fixed on the shaft 116. 85 The cam roller 124 is resiliently held to its cam by a spring 127.

Means are provided for intermittently feeding the controller strip forward from one perforation to the next beneath the fingers 80 between the successive actuations of the typewriting machine from the perforations. As embodied, a feed pawl 130 cooperates with ratchet teeth 131 formed on the controller strip feed roller 82 at one side 95 thereof. The feed pawl 130 is pivoted at 132 to a lever 133, which lever is pivoted at 134 upon the machine frame. At its opposite end, lever 134 carries a cam roller 135, which roller cooperates with a cam 136, fixed on a 100 shaft 116. A spring 137 resiliently impels lever 133 and feed pawl 130 to the initial position.

A detent mechanism is provided at the opposite end of the cylinder 82 which cooperates with feed mechanism just described, and both accurately positions and maintains the cylinder in position. As embodied, a detent lever 140 cooperates with a series of detent teeth 141, formed on the corresponding 110 end of cylinder 82. Lever 140 is pivoted at 142, and is provided with a cam roller 143 which roller runs on a cam 144, fixed on shaft 116. A spring 145 resiliently holds the roller to its cam.

The manner of operation of the mechanism just described is substantially as follows:—

When there are no perforations in the controller strip α , the spring pressed pins 80 ride thereon and maintain the corresponding interponent rods 94 clear of the universal actuating bail 108. When, however, a pin 80 finds its perforation y in the controller sheet α , it drops downwardly under the action of gravity and of its spring 88, and its rod 94 is thereby brought into line with the actuating bail or bar 108. On the next revolution of cam 113, bail 108 will push this interponent 94 forwardly, that is, to the right in Fig. 1, and levers 96 130

and 98 will be rocked, and through engagement with the corresponding pin 40 will actuate the corresponding type lever 2 of the typewriting machine. Immediately thereafter, cam 125 will rock levers 123, 121 to swing restoring bail 120 upwardly, which will engage with interponent rod 94 and thus lift the finger 80 out of its perforation y. Immediately thereafter cam 136 will actuate feed pawl 130 to feed the controller strip x forward one step.

In accordance with one feature of the invention mechanism is provided, and also a controlling instrumentality, whereby the machine may operate continuously to print repeatedly the same letter body, while automatically selecting and printing a different address each time, the mechanism operating automatically without adjustment or manipulation by an attendant. As embodied (Figs. 1, 9, 10 and 11), the controller strip x upon the feed roller 82 is endless, the two ends of the perforated strip z, representing the body portion of the letter, are connected together by a pair of feeding strips 150, adapted to cooperate with successively selected perforated strips or sheets a, representing the different addresses.

The strips 150 and also the edges of the controller strip x are provided at either side with sprocket holes 151, which cooperate with sprocket teeth on the feed roller 82, in the usual manner to insure accurate and uniform feed. In the end of the perforated controller strip x for the letter body are provided perforations 152, which cooperate with the perforated address sheets a.

In Fig. 11 is shown a magazine 153 within which the address strips a are stored in a pile, and are impelled forward by suitable means, such as a spring 154. It will be understood that this mechanism is shown somewhat conventionally, but that in practice any known or suitable form of magazine and feeding mechanism may be provided.

As embodied, a plurality of hooks 156 are formed on the top end of the address sheets a, and these project into the path of, and are in alinement with, the apertures 152 in the tail of the controller strip x. A co-operating feed roller or series of feed discs 157 may be provided. As the holes 152 come into alinement with the hooks 156, the address strip is attached to the controller strip and is carried through the machine, and as it passes over the roller 82 it will print the corresponding address.

As the address sheet a passes over the top of the roller and comes down head first on the other side, the hooks 156 will slip out of the holes 152 and the address sheet a will drop onto any suitable delivery device. After the body of the letter has been printed on the same sheet with the address, the

holes 152 will take a new address sheet out of the magazine 153 preparatory to printing the next letter.

By reason of the disconnectible connections between the key levers 2 of the typewriting machine and the actuating rods 10, the automatic controlling mechanism may be manufactured and sold independently and may be very simply and quickly attached to a typewriting machine or detached therefrom. By unscrewing the screws 12, the typewriting machine may be lifted off from the controlling mechanism, and by setting the typewriting machine in place thereon and turning the screws 12 to proper adjustment, the typewriting machine will operate the controller mechanism to make, that is, perforate the controller sheet, and in turn the controller mechanism, under the operation of the controller sheet, will operate the typewriter.

The invention in its broader aspects is not limited to the specific mechanisms shown and described but departures may be made therefrom within the scope of the accompanying claims without departing from the principles of the invention and without sacrificing its chief advantages.

What we claim is:—

1. An automatic typewriting machine including in combination printing mechanism, means for presenting and intermittently feeding a perforated controller strip comprising a circumferentially recessed cylinder, fingers corresponding to the characters of the printing mechanism and adapted to pass through the corresponding perforations in the controller and into the recesses in the cylinder, and means operated by a finger finding its perforation in the controller strip for actuating the printing mechanism while the controller strip is at rest.

2. An automatic typewriting machine including in combination printing mechanism, means for presenting and intermittently feeding a perforated controller strip comprising a circumferentially recessed cylinder, fingers corresponding to the characters of the printing mechanism and adapted to pass through the corresponding perforations in the controller and into the recesses in the cylinder, and means operated by a finger finding its perforation in the controller strip for actuating the printing mechanism while the cylinder is at rest.

3. An automatic typewriting machine including in combination printing mechanism, means for presenting and intermittently feeding a perforated controller strip comprising a circumferentially recessed cylinder, fingers corresponding to the characters of the printing mechanism and adapted to pass through the corresponding perforations in the controller and into the recesses in the cylinder, means operated by a finger finding its per-

foration in the controller strip for actuating the printing mechanism while the controller strip is at rest, means for restoring the finger, and means for feeding the controller strip.

4. An automatic typewriting machine including in combination printing mechanism, means for presenting and intermittently feeding a perforated controller strip comprising a circumferentially recessed cylinder, fingers corresponding to the characters of the printing mechanism and adapted to pass through the corresponding perforations in the controller and into the recesses in the cylinder, means operated by a finger finding its perforation in the controller strip for actuating the printing mechanism while the cylinder is at rest, means for restoring the finger, and means for rotating the cylinder to feed the controller strip.

5. An automatic typewriting machine comprising a plurality of key levers, a plurality of actuating levers respectively connected to the key levers, means for presenting and intermittently feeding a perforated controller strip, a plurality of fingers for each of the said actuating levers and cooperating with the controller strip, interponents carried by the fingers, means cooperating with a selected interponent for correspondingly operating the respective actuating lever, and means acting on the interponents for restoring the fingers to normal position.

6. An automatic typewriting machine comprising a plurality of key levers, a plurality of actuating levers respectively connected to the key levers, means for presenting and intermittently feeding a perforated controller strip, a plurality of fingers for each of the said actuating levers and cooperating with the controller strip, interponents carried by the fingers, means cooperating with a selected interponent for correspondingly operating the respective actuating lever, and universal means acting on the interponents for restoring the fingers to normal position.

7. An automatic typewriting machine comprising a plurality of key levers, a plurality of actuating levers respectively connected to the key levers, means for presenting and intermittently feeding a perforated controller strip comprising an intermittently rotatable cylinder, fingers corresponding to the actuating levers and cooperating with the controller strip and cylinder, means including interponents movable with the fingers for operating the actuating levers, a universal bar for restoring the fingers, means for intermittently rotating the cylinder, and a common cam shaft and cams for actuating said recording and rotating means.

8. An automatic typewriting machine including in combination printing mechanism, means for presenting and feeding a control-

ler strip, a series of interponents controlled by the controller strip, a universal bar engageable with the interponents, a corresponding series of levers for transmitting power from the interponents to the individual elements of the printing mechanism, for actuating the printing mechanism, means for perforating a controller strip to represent the printing characters, a device for feeding the controller strip to be perforated and a device for feeding the perforated controller strip to operate the printing mechanism.

9. An automatic typewriting machine including in combination a plurality of key levers, a plurality of actuating levers respectively connected to the key levers, a universal operating member, interponents for selectively and operatively connecting the universal operating member and the respective actuating levers, fingers for controlling the action of the interponents, and means for successively feeding perforated controller strips into operative relation with the fingers for successively writing the address and the body of a letter.

10. An automatic typewriting machine including in combination printing mechanism, means for repeatedly presenting and feeding a controller strip representing the body of a letter, and means for attaching successive controller strips representing addresses in predetermined relation to the first-mentioned controller strip.

11. An automatic typewriting machine including in combination printing mechanism, means for repeatedly presenting and feeding a controller strip representing the body of a letter, and means for attaching successive controller strips representing addresses in predetermined relation to the first-mentioned controller strip, and then releasing them from said first-mentioned controller strip.

12. In an automatic typewriter, printing mechanism, selectively operated mechanism including a set of perforation finding fingers for operating the printing mechanism, an endless controller strip representing a body of a letter, an auxiliary controller strip representing an address, and means for successively bringing the two controller strips into controlling relationship with the same set of perforation finding fingers.

13. In an automatic typewriter, the combination of selectively operated means including a set of perforation finding fingers for controlling the printing, an endless controller strip representing a body of a letter, an auxiliary controller strip representing an address, and means for bringing the two strips into successive operative relation with the same set of perforation finding fingers and for thereafter separating the two controller strips.

14. In combination, an endless controller

- strip representing a body of a letter and an auxiliary controller strip representing an address, means for bringing them into proper relation to operate a printing mechanism, 5 and means for attaching them together in a predetermined relation to print the letter.
15. In combination, an endless controller strip representing a body of a letter and an auxiliary controller strip representing an 10 address, means for bringing them into proper relation to operate a printing mechanism, and means for temporarily attaching them together in a predetermined relation to print the letter.
15. 16. The combination with a typewriting machine having key levers, of a mechanism having means for perforating a controller sheet, and controller means controlled by the 20 perforations in the controller sheet for actuating the typewriting machine, and a common means for connecting the perforating means and the controller means, to the key levers of the typewriter, such means being detachably connected to 25 the typewriter key levers.
17. The combination with a typewriting machine having key levers, of a mechanism having means for perforating a controller sheet, and controller means controlled by 30 the perforations in the controller sheet for actuating the typewriting machine, and a series of rods common to the perforating means and the controller means, the rods being detachably connected to the typewriter key levers, and means for rendering either 35 the perforating mechanism or the controlling mechanism operative with respect to said operating means and the typewriter key levers.
40. 18. An automatic typewriting machine including in combination controller strip perforating mechanism, printing mechanism, means cooperatively associating the printing mechanism with the controller strip perforating mechanism, means for presenting and intermittently feeding a perforated controller strip comprising a recessed cylinder, fingers corresponding to the characters of the printing mechanism and adapted to pass 45 through the corresponding perforations in the controller strip and into the recesses in the cylinder, a universal bar for restoring the fingers, and means operated by a finger finding its perforations in the controller strip for actuating the printing mechanism while the controller strip is at rest.
50. 19. An attachment for automatically operating the ordinary manually operated typewriter including in combination means for operatively connecting the printing mechanism of the typewriter with said attachment, means for presenting and intermittently feeding a perforated controller strip comprising a recessed cylinder, fingers corresponding to the characters of the printing mechanism and adapted to pass 55 through the corresponding perforations in the controller strip and into the recesses in the cylinder, a universal bar for restoring the fingers, and means operated by a finger finding its perforations in the controller strip for actuating the printing mechanism while the controller strip is at rest.
60. 20. An automatic typewriting machine including in combination controller strip perforating mechanism, printing mechanism, means cooperatively associating the printing mechanism with the controller strip perforating mechanism, means for presenting and intermittently feeding a perforated controller strip comprising a recessed cylinder, fingers corresponding to the characters of the printing mechanism and adapted to pass 65 through the corresponding perforations in the controller strip and into the recesses in the cylinder, a universal bar for restoring the fingers, and means operated by a finger finding its perforations in the controller strip for actuating the printing mechanism while the controller strip is at rest.
70. 21. An attachment for automatically operating the ordinary manually operated typewriter including in combination controller strip perforating mechanism, printing mechanism, means cooperatively associating the printing mechanism with the controller strip perforating mechanism, means for presenting and intermittently feeding a perforated controller strip comprising a recessed cylinder, fingers corresponding to the characters of the printing mechanism and adapted to pass 75 through the corresponding perforations in the controller strip and into the recesses in the cylinder, a universal bar for restoring the fingers, and means operated by a finger finding its perforations in the controller strip for actuating the printing mechanism while the controller strip is at rest.
80. 22. An automatic typewriting machine including in combination controller strip perforating mechanism, printing mechanism, means cooperatively associating the printing mechanism with the controller strip perforating mechanism, means for presenting and intermittently feeding a perforated controller strip comprising a recessed cylinder, fingers corresponding to the characters of the printing mechanism and adapted to pass 85 through the corresponding perforations in the controller strip and into the recesses in the cylinder, a universal bar for restoring the fingers, and means operated by a finger finding its perforations in the controller strip for actuating the printing mechanism while the controller strip is at rest.
90. 23. An apparatus for attachment to a standard typewriter for operating it automatically, comprising a plurality of rods adapted to be detachably secured to the several key levers of the typewriter, means 95
- 100.
- 105.
- 110.
- 115.
- 120.
- 125.
- 130.

- for presenting and feeding a perforated controller strip, fingers cooperating with the perforations in the controller strip, a power operated device, interponents controlled by the fingers, for coupling the power operated device to the said rods individually and perforating mechanism actuated by the key levers of the typewriter for perforating a controller strip.
- 10 24. An automatic typewriter, comprising in combination printing mechanism, means for feeding a controller strip, means controlled by the controller strip for operating the printing mechanism, cam operated 55
15 detent mechanism for holding the feeding mechanism while the printing mechanism is being operated from the controller strip, a pawl for intermittently operating the feeding mechanism, and means for causing the 20 detent mechanism and pawl to operate sequentially.
25. An automatic typewriter, comprising in combination printing mechanism, means for feeding a controller strip, means controlled by the controller strip for operating the printing mechanism, cam operated 60
25 detent mechanism for holding the feeding mechanism while the printing mechanism is being operated from the controller strip, a 30 pawl for intermittently operating the feeding mechanism, and cam operated means for causing the detent mechanism and pawl to operate sequentially.
26. An automatic typewriting machine including in combination printing mechanism, a plurality of power transmitting bell crank levers for actuating the printing mechanism, means for presenting and intermittently feeding a perforated controller strip, 65
35 fingers for cooperating with the controller strip, a transversely extending universal bar for restoring the fingers, and means controlled by the fingers for operating the bell crank levers.
- 40 27. An automatic typewriting machine including in combination printing mechanism, vertical rods attached to the respective elements of the printing mechanism for actuating such elements, a plurality of bell 70
45 crank levers, one for each of said vertical 50
50
- rods, one arm of each of such levers being engageable with its respective rod, means for presenting and intermittently feeding a perforated controller strip, fingers for cooperating with the controller strip, a transversely extending universal bar for restoring the fingers, and means controlled by the fingers, for operating the bell crank levers.
28. An automatic typewriting machine including in combination printing mechanism, a plurality of power-transmitting bell crank levers for actuating the printing mechanism, means for presenting and intermittently feeding a perforated controller strip, fingers for cooperating with the controller strip, power driven means, interponents, controlled by the fingers, for coupling the power driven means to respective bell crank levers, and a transversely extending bar, acting on the interponents for resting the fingers.
29. In an automatic typewriter, the combination of printing mechanism, selectively operated mechanism including a set of perforation finding fingers for operating the 75
75 printing mechanism, a universal power operated device, interponents controlled by the fingers for individually coupling the power operated device to selected elements of the printing mechanism, a universal device for restoring the fingers to normal position, and means operable by the printing mechanism for perforating a controller strip.
30. In an automatic typewriter, the combination of printing mechanism, selectively operated mechanism for operating the printing mechanism, an endless controller strip for the body of a letter, an auxiliary controller strip for an address, means for 80
85 bringing the two controller strips successively into operative relationship with the same selectively operated mechanism, and means, operable by the printing mechanism, for perforating a controller strip.

In testimony whereof, we have signed our names to this specification.

TASSOS M. COTTAKIS.
TASSO D. METROPOLE.
